(57) **CLAIM**

The ornamental design for a portable electric chainsaw body, as shown and described.

DESCRIPTION

FIG. 1 is a front, right and top perspective view of a portable electric chainsaw body showing our new design;

FIG. 2 is a rear, left and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, right and top perspective view of the portable electric chainsaw body in accordance with our new design illustrating a state in which environmental structures (a battery and a blade) are attached to the portable electric chainsaw body.

The broken lines in the drawings illustrate the environmental structures or portions of the portable electric chainsaw body which form no part of the claimed design.
